SELECTOR BRUSH

Gerald Deakin, New York, N. Y., assignor to International Standard Electric Corporation, New York, N. Y., a corporation of Delaware

Application February 23, 1945, Serial No. 579,368

10 Claims. (Cl. 200—16)

1

My invention relates to electrical contact brushes and more particularly, although not exclusively, to brushes for selector switches for telecommunication systems.

An object of the invention is to provide a contact brush comprising a spring member which is provided with a special brush or brush shoe guide attached to but insulated from the spring member, thus dispensing with separate brush guides proposed heretofore.

According to certain features of the invention, a contact brush comprises a pair of generally parallel brush spring members fixed to a supporting means at one end and provided adjacent the other end with inwardly offset portions or shoes having contact surfaces for wiping over the contact terminals or pins of a bank. Such inwardly offset portions provide at the outer faces of the spring member, transverse recesses over which are fixed blocks or plates of insulating material. Guides are attached to said insulation blocks over said recesses and serve to guide the spring members along a line of terminal contact pins. These guides comprise inwardly and rearwardly converging portions and their inner portions are substantially in the planes of said shoes but are spaced therefrom thus preserving the insulation of the guides from the springs. The shoes are flared outwardly at their edges opposite to those adjacent the effective parts of said guides.

The device of the present invention has many advantages. No insulating material will rub on that part of the pin on which the brush shoe rides. The guide is adjacent to the brush shoe so that no inward bending of the brush shoe will cause the insulator instead of the brush shoe to rub on the pins. The shoe will travel from pin to pin with no or very little drop between pins; thereby not only reducing vibration to a minimum but also increasing the useful rubbing surface to substantially 85 or 90 per cent of the distances between the axes of adjacent pins.

The above and other features will be fully understood from consideration of the following description of one embodiment of my invention taken in conjunction with the accompanying drawings in which:

Fig. 1 is a side elevation of a brush unit;

Fig. 2 is an elevation as seen from the right of Fig. 1;

Fig. 3 is a view of the structure of Fig. 1 as seen from above;

Fig. 4 is a view of the lower part of Fig. 1 on a larger scale;

Fig. 5 is a section on the line 5—5 of Fig. 4;

Fig. 6 is a section on the line 6—6 of Fig. 4; and

2

Fig. 7 is a section taken on the line 7—7 of Fig. 4.

My invention is disclosed as applied to a flat-type selector switch of the kind disclosed in Patent No. 2,330,812 issued to me on October 5, 1943. Only one brush unit is illustrated in the accompanying drawings; but it should be understood that in practice eight or any other suitable number will be mounted on the same brush carriage which is moved back and forth in a reciprocatory manner over the flat terminal bank.

Referring to Figs. 1, 2, 3 and 4 the brush unit comprises a strip 10 of suitable material such as a laminated phenolic sheet adapted to be secured to a brush carriage in any suitable manner. Secured to said strip 10 by rivets or eyelets 11 are two phosphor bronze brush springs 12. The upper portions of the brush springs 12 are formed with lateral extensions 13 for wiping along a feeder bar (not shown).

The free ends of the brush springs 12 are provided with laterally or inwardly displaced parts constituting brush shoes 14 having contact surfaces 15 at the inner sides thereof and adapted to wipe over contact pins 16 linearly arranged. These pins may be made of a hard metal such as phosphor bronze or stainless steel. At one edge each brush shoe 14 is substantially in alignment with the edges of the spring above and below the brush shoe, but at the opposite edge of the spring there is provided a wing or guide 17 turned outwardly, thereby providing an opening flaring outwardly from the shoe 14. At some distance above shoe 14, the springs 12 are provided with lugs or projections 18 which prevent the springs 12 from touching when their brushes leave a pin at the end of a run or traverse. The inward movement of the brushes at the end of a run or stroke is thus reduced or made very small. As a result the movement of the brushes when the end pin is re-engaged will be very small.

At the edges of the brush shoes 14 remote from the guides 17, provision is made of metallic guides 19 secured to the brush springs 12 but insulated therefrom. These guides 19 are made of any suitable material such as phosphor bronze. The contact face of each of said springs is necessarily too short to contact two pins 16 at the same time and therefore a brush shoe might drop down between successive pins 16. Each guide 17 provides a part of which one face is in alignment with the corresponding contact surface so as to lengthen the effective supporting surface without changing the length of the effective contact surface, the guide being insulated from the shoe. With such extended supporting surface,

the brush may engage two successive pins 16 at one time although being in electrical contact with only one pin 16 at a time.

As illustrated, the insulating support for each guide 17 is provided by a block or plate 20 of insulating material such as laminated phenolic material, placed across the recess at the back of the shoe 14 and secured to the springs 12 by suitable means such as eyelets 21. Each guide 17 may be made of a metallic strip preferably of phosphor bronze deformed to provide a flat body 22 secured to insulating plate 20 at its outer face by suitable means such as an eyelet 23, a flat portion 24 inclined inwardly and rearwardly from the outer edge of body 22 and a short flat portion 25 extending rearwardly in alignment with shoe 14 but spaced therefrom. As indicated most clearly in Fig. 4, the insulating plate 20 is cut away to receive the downwardly and rearwardly extending part 24 of the guide 19.

As best shown in Fig. 7, a spring 12 will always be guided by at least one pin 16, even during the period when contact has been broken with one contact pin 16 and has not been established with the next pin.

It should be understood that while I have illustrated only one form of the invention and as applied to only one form of switch it is applicable in other forms and to other forms of apparatus without departing from the invention as defined by the appended claims.

I claim:

1. An electrical contact brush for a selector switch comprising a metallic spring member having a contact surface for successive engagement with a series of stationary terminals, a metallic guide member mounted on said spring member in alignment with said surface and spaced from the forward edge thereof in the direction of movement of said brush, means for electrically insulating said guide member from said spring, said contact surface being shorter in the direction of movement of said brush than the space between adjacent terminals and said guide member extending forwardly in the direction of movement of said brush to engage a terminal before said spring contact surface leaves the succeeding terminal, and means to urge said contact surface towards said terminal.

2. An electrical contact brush according to claim 1 wherein the metallic guide member has a forward surface inclined away from the plane of said contact surface to guide the advancing spring into position for said contact surface to engage the next stationary terminal.

3. The combination with a row of linearly mounted contact pins, of a contact brush movable therealong and comprising a pair of generally parallel metallic spring members engaging opposite sides of said row of pins and having inwardly offset contact portions adjacent corresponding free ends of said spring members, and metal guides for engagement with said pins, insulated from said springs but supported thereby at substantially the same level as said contact portions.

4. The combination according to claim 3 wherein the inwardly offset portions are spaced from the ends of said springs thus providing recesses at the outer faces of said springs, and wherein plates of insulating material are secured across said recesses and said guides are secured to such insulating plates.

5. An electrical contact brush comprising a metallic spring member having an electrical con-

tact surface, supporting means for said spring member, and guiding means mounted on said spring member comprising a block of insulating material secured to said spring member at the side opposite to said contact face and a metallic guide secured to such insulating block and having a part substantially parallel to said contact surface and projecting beyond the lateral edge of said spring member, an inclined part extending rearwardly and inwardly and an inner part extending rearwardly but spaced from the forward edge of said spring member.

6. The combination according to claim 5 wherein a portion of said spring member is offset to provide a transverse recess at one face and at the other face a projection with the contact surface, and the block of insulating material is secured to said spring member across said recess.

7. An electrical contact brush for a selector switch comprising a metallic spring member having a contact surface for successive engagement with a series of stationary terminals and a metallic guide member mounted on said spring member and in alignment therewith but electrically insulated therefrom, said guide member comprising a strip having a part extending across the back of said spring opposite said contact surface and substantially in advance of said spring, a second part extending rearwardly and inwardly to the path of said inner face and a third part extending rearwardly with its inner surface substantially in the path of said contact surface.

8. The combination with a row of contact pins, of a contact brush for movement therealong and comprising a pair of generally parallel metallic spring members having adjacent to corresponding ends inner contact surfaces for making electrical contact with said contact pins, and means for guiding said spring members to effect engagement of said contact surfaces with said pins including for each spring member a metallic guide secured thereto but insulated therefrom and in alignment with said contact surfaces, said metallic spring members being provided with opposed parts to prevent engagement of said contact surfaces when they are carried beyond a terminal contact pin.

9. The combination with a row of contact pins, of a contact brush for movement therealong and comprising a pair of generally parallel metallic spring members having adjacent to corresponding ends inner contact surfaces for making electrical contact with said contact pins, and means for guiding said spring members to effect engagement of said contact surfaces with said pins including for each spring member a metal guide secured thereto but insulated therefrom and in alignment with said contact surfaces, said metallic spring members being provided at their edges remote from said guides with outwardly flared interior surfaces.

10. The combination with a row of contact pins, of a contact brush for movement therealong and comprising a pair of generally parallel metallic spring members having adjacent to corresponding ends inner contact surfaces for making electrical contact with said contact pins, and means for guiding said spring members to effect engagement of said contact surfaces with said pins including for each spring member a metal guide secured thereto but insulated therefrom and in alignment with said contact surfaces, said guiding means comprising at the outer face of each spring member an electrically insulating body secured thereto and each metal guide in-

cluding a flat portion secured to said insulating body and extending toward the next pin to be contacted, a second flat portion inclined inwardly and rearwardly and a third flat portion extending rearwardly with its inner face in alignment with the corresponding contact face but with its rear edge spaced from the edge of the adjacent spring member.
